UNITED STATES PATENT OFFICE.

PETER A. BROUILLETTE, OF SIOUX CITY, IOWA, ASSIGNOR TO THE INVENTIONS
SPECIALTY COMPANY, A COPARTNERSHIP, CONSISTING OF E. O. BLEKRE AND
B. A. RHEINSTROM, OF SIOUX CITY, IOWA.

MATCH-BOX HOLDER.

1,321,414.

Specification of Letters Patent. Patented Nov. 11, 1919.

Application filed January 11, 1919. Serial No. 270,720.

To all whom it may concern:

Be it known that I, PETER A. BROUILLETTE, a citizen of the United States, and a resident of Sioux City, in the county of 5 Woodbury and State of Iowa, have invented certain new and useful Improvements in Match-Box Holders, of which the following is a specification.

The invention contemplates an improved 10 holder for match-boxes of the telescoping type.

Another object of the invention is the production of a telescoping match-box holder adapted to be readily mounted on the 15 steering-wheel or steering-column of a motor-vehicle, and hold the match-box securely yet instantly accessible to the driver.

Still another object of the invention is the production of a match-box holder inexpensive and simple in construction, yet 20 thoroughly durable and dependable in operation.

With these and other objects in view, the invention, consisting in the construction, 25 combination and novel arrangement of parts, will be fully understood from the following description, reference being had to the accompanying drawings, which form a part of this application and in which like 30 characters of reference indicate corresponding parts throughout the several views, of which,—

Figure 1 is a fragmentary plan of a motor-vehicle steering-wheel, with the device of my invention applied thereto;

Fig. 2 is a perspective view of the holder; and

Fig. 3 is an end elevation of the same.

Although I have illustrated and herein 40 after described the preferred embodiment of the invention, I would not be understood as being limited to the specific structure chosen for illustration, for various alterations and modifications may be made in the 45 details of construction and arrangements of parts disclosed, without departing from

the spirit and scope of the invention as defined in the appended claim.

Referring, now, to the illustrations, my improved holder is preferably constructed 50 of a blank metal sheet, the intermediate portion of which serves as the rear wall, 4. The side edge portions are bent at right-angles to the wall, 4, to form side walls, 5; and then laterally toward each other to provide 55 the front wall, 6. The walls are so spaced as to snugly receive the outer case, or cover, 7, of the familiar safety-match-box, within which slides the box proper, 8; and between the overturned edge portions of the sheet, 60 which form the front wall, is left a space, 9, to facilitate the introduction and removal of the cover, 7, into and from the holder.

The lower end portions of the side walls are bent, coincident the ends of the other 65 walls, laterally toward each other, as at 10, the said portions being preferably positioned between and flush with the edges of the front and rear walls. The portions, 10, extend approximately to the free side edges 70 of the wall portions, 6, and the adjacent edges of said end portions are concave, as at 11, to provide an opening in the end wall of sufficient size to receive a person's finger to force the box, 8, from its cover, as shown 75 in Fig. 1.

The side walls of the holder are slotted longitudinally, as at 12, to expose the usual abrasive elements on the sides of the cover for lighting the matches.

Intermediate portions of the side walls and rear wall are sheared transversely of the holder and bent rearwardly to form clamping ears, 13.

The holder is illustrated as being mounted 85 on the spoke, 14, of a motor-vehicle steering-wheel, yet it will be understood that it may be mounted on any suitable support, the holder being so positioned that its rear wall rests on the support, and its clamping ears, 90 13, on opposite sides of the support. A bolt, 15, is then inserted through the ears, on the

opposite side of the support from the rear wall, and by means of the bolt the holder is firmly secured to the support.

Having thus described my invention, 5 what I claim as new and desire to secure by Letters Patent of the United States, is,—

A match-box holder adapted to be mounted on a suitable support and includ-

ing a casing having side walls and a rear wall, and ears extending rearwardly from 10 the rear wall, said ears being cut from the said side walls and rear wall.

In testimony whereof I have hereunto set my hand.

PETER A. BROUILLETTE.
